[57] CLAIM

The ornamental design for a quilted license plate frame, as
shown and described.

DESCRIPTION

FIG. 1 is a top plan view of a quilted license plate frame
showing my new design, the bottom plan view is the mirror
image thereof;

FIG. 2 is a front elevational view of FIG. 1;

FIG. 3 is a right side elevational view of FIG. 1, the left side
elevational view being the mirror image thereof;

FIG. 4 is a rear elevational view of FIG. 1;

FIG. 5 is a sectional view along line FIG. 5—5 of FIG. 1;
FIG. 6 is a top plan view of another embodiment, the bottom
plan view is the mirror image thereof;

FIG. 7 is a front elevational view of FIG. 6;

FIG. 8 is a right side elevational view of FIG. 6, the left side
elevational view being the mirror image thereof;

FIG. 9 is a rear elevational view of FIG. 6; and,

FIG. 10 is a sectional view along line FIG. 10—10 of FIG. 6.
